Attorney.

UNITED STATES PATENT OFFICE.

OPHELIA O. CALEFF, OF BOSTON, MASSACHUSETTS.

GAS-BURNER.

1,381,539.

Specification of Letters Patent. Patented June 14, 1921.

Application filed November 5, 1920. Serial No. 422,017.

To all whom it may concern:

Be it known that I, OPHELIA O. CALEFF, a citizen of the United States, and a resident of Boston, in the county of Suffolk and 5 Commonwealth of Massachusetts, have invented certain new and useful Improvements in Gas-Burners, of which the following is a full, clear, and exact specification.

The object of this invention is the effecting of improvements in that type of gas burners which is adapted to be located within a cooking range, the special features of the improvements relating to means for increasing the heat directed against both the 15 water-front and the oven-wall, and also to better supply the heat to the range-top.

In the drawings forming part of this specification, Figure 1 is a perspective view of a gas burner embodying my improvements. Fig. 2 is a cross section thereof showing its designed location in a range. Fig. 3 is a sectional detail view of one of the valves.

The burning gas is supplied to the burner 25 through a pipe 1 suitably supplied with air, as through an air-supply device 2. This pipe 1 is tapped into a central boss 3 of an H-shaped member 4, from which rises a pipe-section 5. Into the branches 6 of the 30 H-member are tapped two burner tubes 7 provided with burner openings 9.

At the upper end of the vertical section 5 is a T 10, from which a feeder section 11 extends parallel with the burner tubes 7, this 35 section 11 having two X-couplings 12 and 13 from the lateral branches 14 of which project short burner tubes 15. Both the tubes 15 and the X-couplings are provided with burner openings 17.

40 From the branch of the T 10 opposite the feeder section 11, projects a valve-stem and actuating handle 19 constructed for closing the entrance to the section 11 and thereby shutting off wholly or partially the supply 45 of gas thereto, as shown in Fig. 3. Similarly a valve 18 and actuating hand-piece 19 is provided for shutting off the supply of gas to each of the burner tubes 7, both or either, wholly or partially.

50 Beneath the burner tubes 7 and above the supply pipe 1 is located a baffle plate 20 suitably curved as shown in Fig. 2 to fit the same; this plate extending practically the entire length of the burner tubes.

55 As shown in Fig. 2, the gas burner is rested directly upon the grate 21 of the fire

pot 22 of a range, while the cross-wise burner tubes 15 come close beneath the top 23 of the stove. The cross-wise burner tubes 15 are designed to come beneath the canters 40 of the front stove covers in order to concentrate their heat against either these covers, or when the latter are removed, against the bottom of the pot or against placed thereat.

Thus placed, all the heat can be supplied 65 by the cross-wise burner tubes for heating purposes; or the valve 18 of these tubes can be closed and both burner tubes 7 permitted to do the heating for warming both the water-front of the range and the oven; or 70 the water-front can be given all the heat; or the oven can be heated alone, or all the burners can be simultaneously supplied with gas and give the maximum of heat.

The purpose of the baffle plate 20 is to 75 shut off the admission of too much air through the grate, and also to concentrate a supply of heated air to the burner tubes 7. The central portion of the plate being over the supply pipe 1, is brought nearer the 80 burner flame and is strongly heated thereby. Moreover, the concave under surface of the plate 20 provides a pocket for holding therein for a time the air which is rising upward through the grate. This heats the air much 85 more than it could otherwise be, so that when it finally escapes therefrom and rises between the lateral edges of the plate and the faces of the fire pot, it reaches the flaming gas issuing from the burner holes with 90 a maximum temperature, further aiding in the combustion and at the same time incapable of cooling the open or the water front as it rises.

Another purpose in thus arranging the 95 baffle plate is to fasten it in place so that the burner can be shipped without danger of its being forgotten or misplaced. Although for the sake of clearness of illustration, I have shown the baffle plate 20 as flush with 100 the faces of the tube-caps 25, I prefer to press it farther in to bring its terminal edge 26 just within the inner edges of the caps 25 so as to lock it in place thereby.

What I claim is:

105 1. A gas burner for stoves and ranges, comprising burner tubes designed to be located at the bottom of the fire pot, a vertical pipe section rising therefrom, a horizontal feeder section connected with the upper end 110 of said vertical section, two cross-sections of said vertical section, two cross-sections communicating with and supported by said

- horizontal section to come immediately beneath the two stove covers, and means for supplying said tubes and sections with burning gas, said cross-sections having burner openings along their upper surfaces. 4. A gas burner for stoves and ranges comprising a pair of parallel burner tubes, means for supplying them with burning gas, and a baffle plate having its lateral edges located beneath said tubes. 30
5. A gas burner for stoves and ranges comprising a pair of parallel burner tubes, means for supplying them with burning gas, and a baffle plate having its under surface concave and its lateral edges located beneath said burner tubes. 35
2. A gas burner comprising a gas supply pipe, an H-shaped fitting connected with said pipe, burner tubes connected with the outer portions of said fitting, a vertical pipe section rising from and communicating with said fitting, a T mounted on the upper end of said vertical section, a horizontal feeder section supported by said T and having two X-couplings thereto, cross burner tubes projecting laterally from said X-couplings, a valve for said feeder section, and a valve for each of the first-named burner tubes. 6. A gas burner for stoves and ranges comprising two burner tubes each closed at one end, the closing means consisting of a cap screwed thereon, means for supplying 40 burning gas to the other ends of said tubes consisting of a pipe lying midway of and parallel with said tubes, and a baffle plate curved to have its lateral edges located beneath said tubes and its intermediate portion 45 to cover said supply pipe. 40
- 10
- 15
- 18
- 20
- 25
3. A gas burner for stoves and ranges comprising two parallel burner tubes, and a gas supply pipe disposed midway of and parallel with said burner tubes and connected with the latter, and a baffle plate curved to pass above the supply pipe and to have its lateral edges come beneath said burner tubes. 45

In testimony that I claim the foregoing invention I have hereunto set my hand this 3rd day of November, 1920.

OPHELIA O. CALEFF.
